CLAIM

The ornamental design for a jogger's belt, substantially as shown and described.

DESCRIPTION

FIG. 1 is a front elevational view of a jogger's belt showing our new design;

FIG. 2 is a bottom plan view thereof;

FIG. 3 is a rear elevational view thereof;

FIG. 4 is an exploded front elevational view of the belt with the pockets opened;

FIG. 5 is an exploded bottom plan view thereof;

FIG. 6 is an exploded rear elevational view thereof, and

FIG. 7 is a front elevational view of a modified form of a jogger's belt.
